UNITED STATES PATENT OFFICE

108,522

DESIGN FOR AN ENSEMBLE DRESS

John Tuman, Mount Vernon, N. Y.

Application January 11, 1938, Serial No. 74,194

Term of patent 3½ years

To all whom it may concern:

Be it known that I, John Tuman, a citizen of the United States, residing at 403 North Fulton Avenue, Mount Vernon, State of New York and county of Westchester, have invented a new, original, and ornamental Design for an Ensemble Dress, of which the following is a specification, reference being had to the accompanying drawing constituting a part thereof.

Fig. 1 is a front view of the ensemble dress.

Fig. 2 is the rear view of the ensemble dress as shown in Fig. 1.

The characteristic feature of my design resides in the specific embroidery on the lapels, collar, and sleeves of the bolero member of the ensemble and which embroidery matches that on the dress pockets as shown.

I claim:

The ornamental design for an ensemble dress, substantially as shown and described.

JOHN TUMAN.
